UNITED STATES PATENT OFFICE.

FRED M. POLHAMUS, OF SYRACUSE, NEW YORK, ASSIGNOR OF ONE-HALF TO ANNA B. GRAHAM AND GUY M. POLHAMUS, BOTH OF SYRACUSE, NEW YORK.

SNOW PLOW AND CONVEYER.

Application filed July 30, 1925. Serial No. 47,034.

To all whom it may concern:

Be it known that I, FRED M. POLHAMUS, a citizen of the United States of America, of Syracuse, in the county of Onondaga, in the State of New York, have invented new and useful Improvements in Snow Plows and Conveyers, of which the following, taken in connection with the accompanying drawings, is a full, clear, and exact description.

This invention relates to a combined snow plow and conveyer attachment for motor vehicles and involves the use of a supplemental truck having a relatively fixed frame adapted to be rigidly secured to the front end of the chassis frame of the vehicle, and a relatively movable frame extending forwardly from the front end of the fixed frame and hinged thereto to swing vertically, the front end of the hinged frame being provided with a suitable plow blade adapted to be adjusted in more or less close proximity to the surface of the pavement or road bed for removing the snow therefrom as the machine is propelled forwardly.

The hinged plow supporting frame carries an endless conveyer inclining upwardly and rearwardly from the plow blade to a position directly over the front end of the fixed frame for conveying the snow removed by the plow upwardly and rearwardly on to an endless cross conveyer on the fixed frame and thence on to an additional endless conveyer extending upwardly and laterally from a plane below one end of the cross conveyer for the purpose of conveying the snow deposited thereon by the cross conveyer some distance to one side of the road bed out of the way of traffic along the road.

The main object is to provide a snow plow and conveyer attachment of this character which may be applied to standard makes of motor cars without material alteration thereof so that the motive power used in propelling the cars may be applied to the operation of the snow plow and conveyers.

Another object is to provide a system of conveyers arranged in such manner that the snow removed by the plow will be elevated from the road bed and carried to one side thereof as the machine is propelled forwardly.

Another object is to enable the side conveyer to be attached to either side of the

machine in line with the cross conveyer and also to provide for the vertical adjustment thereof to different angles so as to permit the snow to be discharged therefrom at different heights and at different distances relatively to the road bed as may be required according to the depth of the snow at the sides of the road.

A further object is to provide suitable means for transmitting motion from the engine shaft to the several conveyers and for controlling the operation of said conveyers independently of the controllers for the operation of the motor vehicle.

Other objects and uses relating to specific parts of the apparatus will be brought out in the following description.

In the drawings:

Figure 1 is a top plan of a combined snow plow and conveyer attachment ready to be applied to a motor vehicle, portions of the latter being shown by dotted lines, portions of the rear ends of the relatively fixed frame of the attachment and controller being broken away.

Figure 2 is a longitudinal vertical sectional view of the same attachment taken on line 2—2, Figure 1.

Figure 3 is an enlarged transverse vertical sectional view taken on line 3—3, Figure 1.

Figure 4 is a horizontal sectional view taken in the plane of line 4—4, Figure 2, the front portion of the swinging frame and conveyer supported thereby being broken away.

In order that the invention may be clearly understood I have shown a portion of the front end of an automobile chassis frame consisting of the front axle A carrying the usual steering wheels —a— and steering knuckles —b— which latter are provided with the usual crank arms —b'— connected by the usual connecting rod —B—, the latter being provided with the customary operating rod —B'— for turning the wheels upon their respective knuckles for steering purposes.

Portions of the sills —C— of the chassis frame are also shown by dotted lines in Figures 1 and 4 and together with the front axle A constitute the means for supporting the relatively fixed frame of the combined plow and conveyer attachment.

As illustrated, this relatively fixed frame comprises a pair of side bars or rails —1— preferably of angle iron extending forwardly and rearwardly of the machine in parallel transversely spaced relation so as to extend rearwardly beyond the front ends of the sills —C— to which they are clamped by means of bolts —2— and clamping blocks —3— which are interposed between the outer faces of the sills —C— and adjacent portions of the rails —1— as shown more clearly in Figure 4.

The frame bar —1— on the right hand side of the machine is provided with a rearward extension —4— carrying a notched segment —5— and a lever —6— as a part of the mechanism for raising and lowering the front end of the plow supporting frame hereinafter described.

Additional cross bars —8— are rigidly secured to and between the lengthwise bars —1— in parallel spaced relation between the axle —A— and front cross bar —7— for additionally bracing the side rails —1— and also forming convenient bearings for a series of, in this instance, three lengthwise shafts —9—, —10— and —10'— which are journaled in said cross bars —8— in parallel spaced relation, the shaft —9— being substantially co-axial with and directly connected to the crank shaft S of the motor vehicle, said crank shaft being shown by dotted lines in Figure 4.

The other two shafts —10— and —10'— are located equal distances from and at opposite sides of the central shaft —9— for purposes presently described.

The front end of the relatively fixed frame of the attachment is yieldingly supported by a pair of elliptical springs —11— upon a supplemental axle —12— carrying a pair of steering wheels —13— which are connected to the ends of the axle —12— by suitable steering knuckles —14—, Figures 3 and 4.

These steering knuckles are provided with suitable crank arms —15— connected by a rod —16— for simultaneous operation of the steering wheels —13—, one of said knuckles preferably the one on the left hand side of the machine, Figure 4, being provided with an additional crank arm 15' which is connected by a forwardly extending rod —16'— to a supplemental crank arm —16''— on the crank arm —b'— of the steering knuckle for the steering wheel —a— of the corresponding side of the machine whereby when the steering wheels —b— of the machine are operated for steering purposes similar angular movement will be transmitted to the steering wheels —13— for the frame of the attachment.

An upright frame —17— is rigidly mounted upon the horizontal frame bars —1— and cross bar —7— and is provided with longitudinally spaced side walls —18— and ver-

tically spaced horizontal partitions —19— and —20— extending transversely of the machine to form suitable guides for a transversely extending endless conveyer —21—.

A pair of shafts —22— are journaled in suitable bearings in opposite sides of the upright frame between partitions —19— and —20— and are provided with sprocket wheels —23— for receiving and driving the endless conveyer belt —21—, one side of which travels along and upon the upper face of the partition —19— while the opposite side travels along and upon the lower partition —20—.

One end of each of the shafts —22— is provided with a pair of additional sprocket wheels —24— and —24'—, the sprocket wheels —24— being connected by link belts —25— and 25' to sprocket wheels —26— and —26'— on their respective shafts —10— and —10'—.

As previously stated the central shaft —9—, Figure 4, is driven by the crank shaft —S— of the engine and is provided with a pinion —28— meshing with a relatively larger gear —29— which is loosely mounted upon a cross shaft —30—, the latter being journaled in suitable bearings —31— on the frame of the attachment as shown more clearly in Figures 3 and 4.

A vertically movable frame —32— of triangular form in side elevation is pivotally connected at —33— to the center and ends of the front of the rail or bar —7— to extend forwardly therefrom in front of the upright frame —17— for receiving and supporting a plow blade —34— and an endless conveyer —35—.

A cross shaft —36— is journaled in suitable bearings —37— on the underside of the front portion of the frame —32— and is provided with a pair of depending casters —38— adapted to ride upon the surface of the road bed for supporting the front end of the plow frame, said shaft being also provided with upwardly extending crank arms —39— which are connected by rearwardly extending links —40— to additional crank arms —41— on a rock shaft —42—, the latter being journaled in suitable bearings on the lower portion of the rear end of the frame —32—.

This rock shaft —42— is provided with an additional crank arm —43— which is connected by a link —44— to the hand lever —6— on the rear end of the extension —4— of the adjacent side rail —1—, Figure 2, whereby the movement of the lever —6— along the segment —5— will rock the casters —38— about the axis of the rock shaft —36— for adjusting the front end of the plow frame —32— vertically about the axis of the pivots —33— and thereby regulating the position of the plow blade relatively to the road surface,

The plow frame —32— extends laterally equal distances beyond the side rails —1— and longitudinal center of the machine and is provided along its opposite sides with upward flanges —32'— for confining the snow picked up by the plow blade —34— within the limits of the width of the frame and also for concentrating the snow upon the upper side of the conveyer belt —35—.

10 The plow blade —34— is substantially flat and extends from side to side of the frame —32— between the flanges —32'— and serves to lift and deflect the snow upwardly as the machine is propelled forwardly.

15 The conveyer belt —35— extends laterally nearly the full width of the distance between the flanges —32'— with just sufficient clearance at the sides to avoid excessive friction with said flanges and also extends upwardly 20 and rearwardly in an inclined plane from a point in proximity to the rear edge of the blade —34— to the rear end of the frame —32— and has its upper side supported by a transverse guide plate —45— which extends laterally from side to side of and between the flanges —32'— and is preferably secured thereto and to portions of the frame —32—.

25 The upper rear portion of the conveyer belt —35— is carried by sprocket wheels —46— which are secured to a cross shaft —47— on the upper rear portion of the frame —32—.

30 The opposite ends of the shaft —47— are provided with sprocket wheels —48—, Figure 1, connected by link belts —49— to additional sprocket wheels —50— on the opposite ends of the shaft —30— as shown in Figure 4 whereby the rotation of the shaft —30— will transmit rotary motion to the shaft —47— and conveyer belt —35—.

35 The lower front end of this conveyer belt is mounted upon suitable sprocket wheels —51— on a shaft —52— which is journaled in suitable bearings in the opposite sides of the lower front end of the frame —32— adjacent the rear edge of the plow blade —34—.

40 As previously stated the gear —29—, Figures 3 and 4, is loosely mounted upon the shaft —30— but is provided with a clutch face adapted to be engaged by a clutch member —29'— which is splined on the shaft —30— for axial movement into and out of engagement with the clutch gear —29—.

45 An upright shifting lever —53— has its upper end pivoted at —54— to a bar —55— on the upright frame —17— and its lower end engages an annular groove in the clutch member —29—, the intermediate portion of said lever —53— being connected by a link —56— to a crank arm —57— on a rock shaft —58— which is journaled in suitable brackets —59— on the frame members —4—

50 and —7—, Figures 2 and 3, the rock shaft —58— being provided with an upwardly extending offset handle —58'— by which it may be rocked in its bearings —59— for shifting the clutch —29'— into and out of engagement with the clutch gear —29—.

55 It is now evident that when the clutch —29'— is engaged with the clutch gear —29—, rotary motion will be transmitted from the engine driven shaft —9— to the counter shaft —30— and that this rotation of the shaft —30— will transmit rotary motion to the conveyer belt —35— through the medium of the link belts —49— so that when the machine is propelled forwardly 60 the plow blade —34— will pick up the snow from the pavement or road bed and deflect it upon the upper side of the conveyer belt which in turn will carry the snow upwardly and rearwardly and deposit it upon the upper surface of the cross belt conveyer —21—.

65 *Cross belt conveyer.*

70 The cross conveyer belt —21— extends equal distances from and at opposite sides of the center of the machine and slightly beyond the opposite sides of the primary conveyer —35— for receiving the snow deposited thereon by the primary conveyer and discharging the snow at one side or the other of the road bed.

75 That is, provision is made for driving this cross conveyer in either direction and for this purpose a pair of gears —60— and —60'— are loosely mounted upon the center shaft —30— at opposite sides of the gear —29— and its clutch —29'— with their bevel teeth facing each other and engaged respectively with pinions —61— and —61'— on their respective shafts —10— and —10'—.

80 These gears —60— and —60'— are provided on their inner ends with clutch teeth adapted to be engaged by clutch collars —62— and —62'—, both of which are splined upon the shaft —30— for axial movement into and out of engagement with their respective gears —60— and —60'—.

85 Suitable shifting levers —63— and —63'— similar to the shifting lever —53— are arranged in upright positions at opposite sides of said levers —53— and have their upper ends pivoted at —64— and —64'— to suitable cross bars —65— and —65'— on the upright frame —17— as shown in Figure 3, the lower ends of said levers being engaged in annular grooves in their respective clutch collars —62— and —62'— for shifting the latter into and out of engagement with their respective clutch gears —60— and —60'— as the levers —63— and —63'— are rocked in reverse directions.

90 The intermediate portions of these levers —63— and —63'— are connected by links —66— and —66'— to a central lever —67— which is pivoted at —68— to the frame —17— and has its upper end pivoted at —69— to a bar —70— on the upright frame —17— as shown in Figure 3, the lower end of the bar —70— being engaged in an annular groove in the clutch gear —60'— so that the latter will be shifted into and out of engagement with the clutch gear —60— as the central lever —67— is rocked in reverse directions.

95

—66— and —66'— to suitable crank arms —67— and —67'— on their respective rock shafts —68— and —68'— which are journaled in suitable bearings in the brackets 5 —59—, said rock shafts —68— and —68'— being provided with offset handles —69— and —69'— by which they may be operated.

As previously explained the sprocket wheels —26— and —26'— on the shafts 10 —10— and —10'— are connected by separate link belts —25— and —25'— to additional sprocket wheels on the rear ends of the sprocket shafts —22— carrying the cross conveyer —21—.

15 It is now clear that if it is desired to discharge the snow from the cross conveyer to the left hand side of the machine the rock shaft —68— will be operated by means of its handle —69— to shift the corresponding 20 clutch —62— into engagement with its clutch gear —60— whereby motion will be transmitted from the engine driven shaft —30— to the left hand sprocket shaft —22—, Figure 3, through the medium of the corresponding link belt —25— thereby 25 moving the upper side of the conveyer belt —21— in the direction indicated by arrow —x—, Figure 3.

On the other hand, if it is desired to discharge the snow from the cross conveyer belt to the right hand side of the machine the rock shaft —68'— will be operated to shift its corresponding clutch —62'— into engagement with the clutch gear —60'— after the 30 clutch —62— has been released whereby motion will be transmitted from the shaft —30— to the right hand sprocket shaft —22—, Figure 3, to move the upper side of the conveyer belt —21— in the direction indicated by arrow —y—.

In case the snow is excessively deep or banked at the side of the road it is necessary to provide means for conveying the snow discharged by the horizontal conveyer 21 to a 45 greater height and at a further distance from the road bed and for this purpose is provided a vertically movable side frame —70— carrying an additional conveyer belt —71— and suitable sprocket shafts —72— 50 as shown in Figures 1 and 3.

The frame —70— is pivoted near one end —73— to the adjacent side of the upright frame —17— at a point some distance below the adjacent end of the cross conveyer belt 55 —21—, said frame —70— and conveyer —71— being adjustable vertically to different angles about the axis of the pivot —73— and is held in its adjusted positions by stay chains or cables —74— which are attached 60 at one end to the frame —70— and are adapted to engage suitable anchor hooks —75— on the upper end of the adjacent side of the upright frame —17— as shown in Figures 1 and 3.

65 The frame —70— may be hinged to either

side of the upright frame —17— according to the direction of movement of the upper side of the cross conveyer belt —21— and for this purpose each side of the upright frame —17— is provided at its upper end 70 with the hooks —75— for receiving the chain —74—.

The sprocket shafts —72— are journaled in suitable bearings on opposite ends of the frame —70— which is provided with a guide 75 plate —76— along and upon which the upper side of the belt is adapted to travel and together with the side flanges as —77— of the frame —70— constitutes a guide chute through which the snow is carried by the 80 upper side of the conveyer —71—.

The side conveyer —71— and its supporting frame —70— are shown as mounted upon the left hand side of the machine and in order that it may be used at either side of 85 the machine the sprocket shafts —22— are provided with additional sprocket wheels —24— and —24'— while the lower sprocket shaft —72— of the side conveyer —71— is provided at its opposite ends with sprocket 90 wheels —78— and —24'— either of which is adapted to be connected by a chain belt —80— to one of the sprocket wheels —24' or —24— according to the side of the machine at which a supplemental conveyer —71— is 95 placed or according to the direction of movement of the conveyer belt —21—.

Operation.

When the attachment is properly adjusted 100 for use upon the front end of a motor vehicle in the manner described for use in removing snow from the road surface the front end of the engine shaft —S— will be in clutch engagement with the rear end of the 105 driven shaft so that when the engine is operated it will transmit rotary motion to the gear —29— and by shifting the clutch —29'— into engagement with said gear the 110 rotary motion will be transmitted to the shaft —30— for operating the conveyer belt —35— in the direction indicated by arrow —z—, Figure 2.

Now, if the machine is propelled along the road bed under its own power the front end 115 of the frame —32— may be adjusted into more or less close relation to the surface of the road bed by the angular adjustment of the casters —38— about the axis of their supporting shaft —36—, this adjustment being effected by the adjustment of the lever —6— along the segment —5— and locking it to said segment in its adjusted position by any suitable means provided on the lever.

As the machine continues to move along 120 the road bed the snow will be picked up by the plow blade —34— and deflected therefrom on to the lower end of the conveyer —35— which in turn will carry the snow upwardly and rearwardly and discharge it 125 130

upon the upper face of the cross conveyer —21—.

Then if the snow is to be discharged to the left hand side of the machine the left hand clutch —62—, Figure 4, will be shifted into engagement with its corresponding gear —60— thereby rotating the shaft —10— and, through the medium of the corresponding link belt —25— transmitting rotary motion 19 to the cross conveyer —21—.

At the same time the conveyer belt —71— will be operated by the link belt —80— to carry the snow deposited thereon by the cross belt —21— upwardly and laterally for 15 discharging the same a further distance to one side of the road bed.

What I claim is:

1. In a combined snow plow and conveyer attachment for motor vehicles, an attachment frame having means for securing it to the front end of the chassis frame of the vehicle so as to extend forwardly therefrom, a shaft journaled on said frame in alignment with the crank shaft of the engine and provided with means for coupling it to said crank shaft, a conveyer belt mounted on the frame and movable transversely of said shaft, a supplemental frame hinged to the front end of the attaching frame to swing vertically and having its front end provided with a plow blade, a conveyer belt mounted on the supplemental frame and inclined upwardly and rearwardly from its forward end, and means for transmitting motion from the cross shaft to the second named conveyer belt. 95
2. In a combined snow plow and conveyer attachment for motor vehicles, an attachment frame having means for securing it to the front end of the chassis frame of the vehicle so as to extend forwardly therefrom, a shaft journaled on said frame in alignment with the crank shaft of the engine and provided with means for coupling it to said crank shaft, a cross shaft journaled on the frame, clutch controlled means for transmitting motion from the engine driven shaft to the cross shaft and separate clutch controlled devices actuated by the cross shaft for transmitting motion to the conveyer belt 85 and for reversing the direction of such motion, a supplemental frame hinged to the front end of the attaching frame to swing vertically and having its front end provided with a plow blade, a conveyer belt mounted on the supplemental frame and inclined upwardly and rearwardly from its forward end, and means for transmitting motion from the cross shaft to the second named conveyer belt. 100
3. A combined snow plow and conveyer attachment for motor vehicles as in claim 1, in which means operable at will is provided for rocking the supplemental frame for its pivot. 105
4. A combined snow plow and conveyer attachment for motor vehicles as in claim 1, in which a rock shaft is journaled in suitable bearings on the underside of the supplemental frame and is provided with casters 50 for engagement with the pavement, and means for rocking said shaft and casters thereon angularly for raising and lowering the front end of the supplemental frame about the axis of its hinge connection with the attaching frame. 110
5. In a combined snow plow and conveyer attachment for motor vehicles, an attaching frame having means for securing it to the front end of the chassis frame of the vehicle, an engine driven shaft journaled on the attaching frame in alignment with the crank shaft of the engine and provided with means for driving connection with said crank shaft, a cross shaft journaled on the attaching frame, clutch controlled means for transmitting motion from the engine driven 115
6. In a combined snow plow and conveyer attachment for motor vehicles, an attaching frame having means for securing it to the front end of the chassis frame of the vehicle so as to extend forwardly therefrom, a shaft journaled on said frame in alignment with the crank shaft of the engine and provided with means for coupling it to said crank shaft, a cross shaft journaled on the frame, clutch controlled means for transmitting motion from the engine driven shaft to the cross shaft and separate clutch controlled devices actuated by the cross shaft for transmitting motion to the conveyer belt 120 and for reversing the direction of such motion, a side frame adapted to be hinged to either side of the attaching frame for vertical adjustment to different angles, means for holding the side frame in its adjusted position, a conveyer belt mounted on the side frame to receive snow from the first-named conveyer, and means for transmitting motion from the first-named conveyer belt to the second-named conveyer belt. 125
7. In a combined snow plow and conveyer attachment for motor vehicles, an attaching frame having means for securing it to the front end of the chassis frame of the vehicle, an engine driven shaft journaled on the attaching frame in alignment with the crank shaft of the engine and provided with means for driving connection with said crank shaft, a cross shaft journaled on the attaching frame, clutch controlled means for transmitting motion from the engine driven 130

- shaft to the cross shaft, additional shafts journaled on the frame at opposite sides of and parallel with the engine driven shaft, separate clutch controlled devices for transmitting motion from the cross shaft to said additional shafts, a supplemental frame hinged to the front end of the attaching frame to swing vertically and having its front end provided with a plow blade, an endless conveyer mounted on the supplemental frame to move lengthwise of the attaching frame, means for transmitting motion from the cross shaft to said conveyer, an additional conveyer mounted on the attaching frame to move transversely thereof at the rear of the first-named conveyer for receiving snow therefrom and separate devices for transmitting motion from said additional shaft to the transversely moving conveyer.
8. In a combined snow plow and conveyer attachment for motor vehicles, an attaching frame having means for securing it to the front end of the chassis frame of the vehicle, an engine driven shaft journaled on the attaching frame in alignment with the crank shaft of the engine and provided with means for driving connection with said crank shaft, a cross shaft journaled on the attaching frame, clutch controlled means for transmitting motion from the engine driven shaft to the cross shaft, additional shafts journaled on the frame at opposite sides of and parallel with the engine driven shaft, separate clutch controlled devices for transmitting motion from the cross shaft to said additional shafts, a supplemental frame hinged to the front end of the attaching frame to swing vertically and having its front end provided with a plow blade, an endless conveyer mounted on the supplemental frame to move lengthwise of the attaching frame, means for transmitting motion from the cross shaft to said conveyer, an additional conveyer mounted on the attaching frame to move transversely thereof at the rear of the first-named conveyer for receiving snow therefrom and separate devices for transmitting motion from said additional shaft to the transversely moving conveyer, a third conveyer extending laterally from one side of the second-named conveyer for receiving snow therefrom, and means for transmitting motion from the second-named conveyer to the third conveyer.

In witness whereof I have hereunto set my hand this 16th day of July, 1925.

FRED M. POLHAMUS.
